UNITED STATES PATENT OFFICE.

DAVID M. TILDEN, OF SPRINGFIELD, MASSACHUSETTS.

CARBURETER

978,076.

Specification of Letters Patent.

Patented Dec. 6, 1910.

Application filed February 15, 1910. Serial No. 544,044

To all whom it may concern:

Be it known that I, DAVID M. TILDEN, a Swedish subject, and resident of Springfield, in the county of Hampden and State of Massachusetts, have invented certain new and useful Improvements in Carbureters, of which the following is a full, clear, and exact description.

This invention relates to carbureters, and more especially to that class thereof which are employed in connection with internal-combustion engines and in which a liquid fuel is gasified or vaporized by a current of air which thus becomes charged with vapor and is subsequently drawn as "explosive charges" into the engine cylinders.

My invention has for its object the improved construction of a device of this character in which all danger of back-firing into the liquid fuel shall be reduced to a minimum, and which, furthermore, shall be of very simple and efficient construction.

The invention has been illustrated in the accompanying drawings in which—

25 Figure 1 is a central vertical section through my improved carbureter. Fig. 2 is a horizontal section on line 2, 2 of Fig. 1. Fig. 3 is a similar section on line 3, 3 of Fig. 1, and Fig. 4 is a similar section on line 4, 4 of Fig. 1.

Briefly stated liquid fuel such as gasolene is admitted near the central portion of the carbureter by a pipe which is normally closed by a valve which at the same time serves as a baffle-plate which is seated to close said pipe by a spring which may be accurately gaged to offer a certain resistance, while at the same time the amount of opening of said valve may be accurately controlled, and in the present instance an air-chamber is disposed around the fuel inlet pipe, the top of which is closed by a plate having a number of openings which in turn may be wholly or partially closed by a regulating-plate forming the bottom of the mixing-chamber, and a similar construction prevails for permitting the passage of the mixture into the outlet pipe. The entire organization being such that the air rushing into the mixing-chamber will come in direct contact with the underside of the valve for the purpose of raising the same, so that by virtue of the air-regulation in connection with the adjustment of the spring pressure on the valve the most economical and best results will be obtained.

Referring to the drawings, the numeral 10 denotes the carbureter-casing comprising a pair of chambers 11, 12 which are separated from each other by a partition 13 having a series of openings 14 through which the gases established in the receiving-chamber disposed below the chamber 11 will pass as controlled by a valve-plate 15 which has openings 16 adapted to register with the openings 14 above mentioned, and which constitutes the upper closing of the receiving-chamber proper.

The receiving-chamber is herein denoted by the numeral 20 and consists substantially of a hollow cylindrical box closed at its upper end by the plate 15 above mentioned, and having its bottom closed by a plate 21 provided with openings 22 to permit the admission of air thereinto as controlled by the position of these openings relative to similar openings 23 provided in a plate 24 which is secured to, or forms a part of, the bottom cover 25 for the lower carbureter-section 12. In order to permit the proper assemblage of the receiving-chamber 20 into the lower carbureter-chamber 12, the bottom of the latter is formed open, so that the receiving-chamber may be inserted thereinto, and the bottom of the section 12 is then closed by the bottom-cap 25 above mentioned, which is in screw threaded engagement with the casing 12 and may be thus adjusted vertically to secure proper positioning of the mixing-chamber 20 within the casing vertically, while a check-nut 26 may be employed to firmly hold the cap 25 in its adjusted position.

Preferably made integral with the cap 25, is a tubular nipple 27 which also projects through the bottom-plate 21 of the receiving-chamber, and which at its upper end is normally closed by a valve indicated in a general way by V; this valve extending for considerable distance beyond the nipple 27 and of such size relative to the openings 22 and 23 that when a current of air passes upward through said openings, said current of air will come in direct contact with the underside of the valve V and raise the same. In connection with this force it may be stated that according to the amount of free opening of the apertures 22 and 23 as controlled by the position of the receiving chamber relative to the cap 25, a certain throttle thereof may take place, it being understood that the less free passage such

openings afford to the inrushing air, the less effective pressure will be exerted upon the valve V to raise the same and vice versa.

The valve V is provided with a series of small concentrically disposed perforations 28, so that all the inrushing air will not be obliged to pass around the outside of the valve-plate V and that consequently such gasolene as emerges from the nipple 27, 5 (which is connected with the gasolene supply-pipe 30) may in part be drawn through said perforations and vaporized and subsequently still further mixed with the air-chamber 20 in a thorough and efficient 10 manner.

In its preferred construction, the cap 25 has a cylindrical flange 31 upon which is mounted for rotative adjustment, an air-distributing chamber 32 having an inlet conduit 33 which is open to the atmosphere so that when suction is applied as for instance by the piston movement of the gas engine, connected with the outlet conduit 34 of the device, air will be drawn from the air-device, 20 chamber 32 through the openings 22, 23, thus raising the valve V and permitting gasolene to enter the receiving-chamber 20 where it naturally will be mixed with the air into a gaseous compound which finds its 25 exit through the openings 16 and 14 into the outlet conduit 34.

Means are provided for resisting the opening of the valve V according to the grade of liquid fuel employed, it being well known 30 that the higher grade the liquid fuel is, the less amount of such fuel is required to produce the proper explosive mixture. These means consist in the present instance of a spring 35 surrounding the valve stem 36 35 which is guided for vertical movement in a sleeve 37 extending through and screw threaded in the carbureter casing as clearly shown in Fig. 1, so that said sleeve 37 may be raised or lowered relatively to the casing as required to produce proper tension of the 40 spring 35 which is interposed between the valve and the lower end of said sleeve. When properly adjusted, said sleeve 37 may be locked in place by a check-nut 38, as 45 shown. Means are also provided whereby the amount of opening movement of the valve V may be controlled, these means consisting of an abutment-rod 39 in screw 50 threaded engagement with the interior of the sleeve 37 and adapted to be held in adjusted position by a check-nut 40 applied to the upper end thereof.

From the foregoing, it follows that the present device is adapted to control, first: 55 the amount of air entering into, and leaving, the mixing-chamber 20 by virtue of its being mounted for rotation within the casing 12 and as may be actuated by an arm 41 secured to the mixing-chamber 20 and passing 60 through a slot 42 provided therefor in

the carbureter-casing 12. Second: to vary the admission of fuel liquid into the mixing chamber in accordance with the quality or grade of such liquid; and third: to control the amount of opening of the valve irrespective of the spring pressure exerted thereon as above mentioned. Furthermore, the present device is so constructed that the interior mixing-chamber will always be in communication with the atmosphere irrespective of the fact whether the openings 22 and 23 are in register or not, so that in case of the explosion of the mixture in the chamber 20, a vent will be provided therefor as is for instance shown in Figs. 1 and 2 in 70 which the cap is illustrated as having a series of perforations 45, while the mixing-chamber has similar perforations 46 both of which are in constant communication with each other either through direct passage 75 from one end to the other or by virtue of a space left between the bottom-plate 21 of the mixing-chamber 20 and the upper face of the plate 24 of the cap 25. It may be noted in the present instance the mixing-chamber has both its upper and lower plates provided with the openings 16 and 22, respectively, so that the rotation of the mixing-chamber will result in varying the size of the free openings or passages of the same, 80 simultaneously, these openings, however, not being sufficiently large to permit the insertion of the valve-plate V so that the cylindrical wall of the mixing-chamber 20 is provided with an opening 50 through which 85 said valve may be placed in position and assembled with its co-operative parts.

Many changes may be made in the construction and organization of the device without departing from the spirit of the invention. 90

I claim:—

1. A carbureter comprising a casing having openings in the top and two sets of openings in the bottom thereof, a drum forming a receiving chamber and rotatively mounted within said casing, there being openings formed in the top and the bottom of said drum, and there being additional openings formed in the bottom of the drum adapted to register with the openings of the casing, a fuel supply pipe passing through the casing and projecting into the interior of the drum, a spring controlled fuel valve for controlling the fuel supply pipe, said valve carrying a horizontally disposed disk of considerably greater diameter than the fuel supply pipe, there being a plurality of openings formed through said disk as and for the purposes set forth.

2. The combination with a casing comprising an upper chamber and a lower chamber separated from each other by an apertured partition, a carbureting chamber comprising a hollow cylindrical box having

its top plate apertured for coöperation with said partition, and also having a lower apertured plate, of a cap for the lower chamber and comprising an air-receiving chamber 5 having an apertured partition for coöperation with the bottom plate of the carbureting-chamber, a fuel-supply passing through said air-chamber into the carbureting-chamber and a valve for the fuel-supply and ex-

tending over the apertures in the bottom- 10 plate of the carbureting-chamber.

Signed by me at Springfield, Mass., in presence of two subscribing witnesses.

D. M. TILDEN.
